VENETIAN BLIND

Ernest Dennen, Beverly Hills, Calif., assignor to Hunter Douglas Aluminum Corporation, Riverside, Calif., a corporation of Delaware

Application November 14, 1955, Serial No. 546,604

3 Claims. (Cl. 160—176)

The present invention relates to Venetian blinds, and its primary object is to provide a blind wherein the slats can be tilted closed and then pressed tightly together against one another so as to exclude light almost completely. Full closure blinds of this type are particularly useful in school classrooms and other institutions, where the room must be darkened to an extremely low level of illumination for projection of motion pictures or slides, or for television viewing. Such blinds are also desirable for bedrooms, where occupants must sleep during the daytime.

When conventional Venetian blinds are tilted closed, the slats are held apart slightly by the lift cords, which pass upwardly through holes in the slats from the bottom rail to the head rail, and this separation of the slats permit an undesirable amount of light to pass through the blind. One solution to the problem of securing full closure of Venetian blind slats was proposed by Bucher and Skiver in their United States Patent No. 2,646,115, granted July 21, 1953, wherein the slats are provided with notches in the edges, which permit the slats to drop down slightly along an arcuate path, so that the bottom edge thereof projects below the cross rungs of the ladder tapes and engages the slat below. The edge notch also provides clearance for the lift cord when the slats are tilted fully closed.

While the blind of the said patent is a great improvement over conventional Venetian blinds and has been widely accepted by public schools throughout the country, it is adversely affected by any bow, or camber, or twist in the slats, all of which are fairly common defects in crowned sheet metal slats. These defects are most noticeable in wide blinds, and an objectionable amount of light may be admitted by the blind if all of the slats are not perfectly true and straight. Another important object of the present invention, therefore, is to minimize or eliminate altogether any light leakage due to bowed, cambered, or twisted slats. This is accomplished by means of a pivoted closer which engages the tilted slats from opposite side thereof and presses them firmly together.

A further object of the invention is to provide a full closure Venetian blind wherein the slats are constrained against fluttering in the wind when the blind is fully closed. Wind-flutter is highly objectionable because of its distracting effect in schoolrooms where motion pictures or slides are being projected, and heretofore the only solution has been to lock the slats to the ladder tape rungs, which is a time consuming operation, and has certain disadvantages. In the present invention, the engagement of the slats by the pivoted closer serves to hold the slats firmly against wind flutter.

The foregoing and other objects and advantages of the present invention will become apparent to those skilled in the art upon consideration of the following detailed description of the preferred embodiment thereof, reference being had to the accompanying drawings, wherein:

2

Figure 1 is an elevational view of a full closure Venetian blind embodying the principles of the invention;

Figure 2 is an enlarged cross section of the same, taken at 2—2 in Figure 1;

Figure 3 is a view similar to Figure 2, but showing the slats in the fully tilted and tightly closed position, the ladder tape and cord in the background being omitted for the sake of clarity;

Figure 4 is a still further enlarged cross-sectional view, taken at 4—4 in Figure 1;

Figure 5 is a fragmentary elevational view of one of the slats, taken at 5—5 in Figure 2; and

Figure 6 is a view similar to Figure 5, but showing the slat in the fully tilted position, as seen at 6—6 in Figure 3.

In the drawings, the blind of my invention is designated in its entirety by the reference numeral 10, and is mounted in a window frame comprising a sill 11, jambs 12 and 13, and lintel 14. The blind 10 includes a tilttable headrail 15, which is supported at one end by a conventional tilter unit 16, and at the other end by a pivot bracket 17. Attached to the headrail near opposite ends thereof are two ladder tapes 20, which support a plurality of horizontally disposed slats 21 in a vertically spaced array. The tapes 20 are attached at their bottom ends to a bottom rail 22.

Each of the ladder tapes 20 consists of two laterally spaced side tapes 23 and 24, which are connected together by vertically spaced rungs 25. The rungs 25 are somewhat less than one-half the width of the tapes 23, 24, and are staggered alternately on left and right hand sides of the center line of the tapes, with space left between them, through which a lift cord 26 passes.

The lift cord 26 is attached to the bottom rail 22 and passes upwardly through cord holes 30 in the slats to pulleys 31 which are journaled on brackets 32 mounted

on the lintel 14. From the pulleys 31, the cords 26 extend horizontally to the right-hand end of the blind, where they pass through a cord lock 33 and hang downwardly therefrom. The slats 21 are formed of thin sheet metal and are crowned, as shown in the cross-sectional views,

so as to stiffen them against sagging. The cord holes 30 are elongated slots or apertures formed in the slats between the side tapes 23, 24 of the ladders, and are offset to one side of the longitudinal center line of the slat, as best shown in Figure 5. When the slat is fully tilted in the normal closed position, as in Figures 3 and 4, the major portion of the cord hole 30 lies within the top one-half thereof. The purpose of this lateral offset of the cord hole is to locate the top end of the hole in the upper portion of the tilted slat, where there is a maximum of horizontal projection for each increment of width, owing to the curvature of the crowned slat and the slight tilt of the latter toward the right hand side, as viewed in Figure 4.

Formed in the edge of the slat that lies at the bottom when the slats are tilted, is a notch 31. The notch 31 is aligned with the cord hole 30, and its width and depth are at least equal to the diameter of the cord 26. The purpose of the notch 31 is to provide clearance for the cord in passing under the bottom edge of the slat, as shown in Figure 4; and the notch 31 and the cord hole 30 combine to provide a continuous open passageway for the lift cord when the slats are fully closed in the normal direction illustrated in the drawings, wherein the concave side of the slat faces into the room.

Each of the slats 21 overlaps the slat below by a substantial amount, as shown in Figure 4, and the bottom edge of the slat abuts against the top surface of the slat below, except for a very slight separation of the slats at the ladder tapes due to the thickness of the rung 25. This full closure condition of the slats is obtained only when the slats are straight and true for their entire length; and any bow, or twist, or camber of the slats causes the

bottom edge thereof to bend out away from the slat below, leaving a gap through which light can pass. To overcome this condition, I provide two pivoted closers 32 adjacent the ladder tapes 20, which function to press the slats tightly together, so that there can be no separation between them.

Each of the pivoted closers 32 comprises a pair of axially aligned pivoted members 33 and 34 at the top and bottom of the blind, which are connected together by a pair of parallel rods 35 and 36, extending along opposite sides of the slats 21. The top member 33 is pivoted on a bracket 40 which is secured by screws to the lintel 14. Intermediate its ends, the bracket 40 drops down slightly to provide an opening for passage of the horizontally extending portions of the lift cords 26. The bottom member 34 is pivoted on a bearing support member 41 that is attached to the sill 11. Both the bottom members 34 may be provided with handles 42 for independent operation, as shown herein, or the bottom members may be linked together to turn in unison, with only one of the members being provided with a handle.

When the tilter 16 is operated by a control cord 43, the top rail 15 is tilted, causing all of the other slats 21 to be tilted by the ladder tapes 20 to the fully closed position shown in Figure 4. To close the slats more firmly together and secure them against wind flutter, the closers 32 are then turned to the angled position shown in Figure 6. This brings the rods 35, 36, in toward the plane of the slats and causes them to press the slats together from opposite sides thereof. The closers 32 may be provided with suitable friction means (not shown) to hold the same in the closed position.

To open the blinds, the closers 32 are swung around to the position shown in Figure 5, perpendicular to the plane of the slats, and the operation of the tilter 16 is reversed. In this position of the closer 32, the slats 21 may be tilted to the horizontal position without touching the rods 35, 36, since the rods are spaced apart a distance slightly greater than the width of the slats.

While I have shown and described in considerable detail what I believe to be the preferred form of my invention, it will be understood that various changes may be made in the shape and arrangement of the several parts thereof without departing from the broad scope of the invention, as defined in the claims.

I claim:

1. A full closure Venetian blind comprising a plurality of horizontally disposed, vertically spaced slats, means for tilting said slats between open and closed positions, at least two lift cords extending vertically through said slats from top to bottom, each of said slats having cord holes provided therein through which said lift cords pass, said slats having notches in one edge aligned with said cord holes, the width and depth of said notches being at least equal to the diameter of said lift cord, said one edge of said slat being disposed at the bottom and overlapping the top edge of the slat below when the slats are tilted

closed in one direction, said notch and said cord hole providing a continuous open passageway for said lift cord when said slats are fully closed in said one direction, and means pivotally supported at the top and bottom of said blind for turning about a vertical axis and having members spaced radially from said axis engaging said slats on opposite sides thereof to press the same tightly together in the vertical plane of said lift cords when the slats are in fully tilted position.

10. 2. A full closure Venetian blind comprising a plurality of horizontally disposed, vertically spaced slats, means for tilting said slats between open and closed positions, a pair of axially aligned pivoted members at the top and bottom of the blind, said members being connected together by parallel rods extending along opposite sides of said slats, and means for turning said members so as to bring said rods in toward the plane of said slats, said rods engaging opposite sides of said slats to press the slats tightly together in a vertical plane taken through the pivot axes of said aligned pivoted members.

15. 3. A full closure Venetian blind comprising a plurality of horizontally disposed slats, at least two ladder tapes supporting said slats in vertically spaced array, means connected to said ladder tapes to manipulate the same so as to tilt said slats between open and closed positions, at least two lift cords extending vertically through said slats from top to bottom, each of said slats having elongated cord holes provided therein through which said lift 20 cords pass, said cord holes being disposed transversely of said slats and offset to one side of the longitudinal centerline thereof, said slats having notches provided in the edge thereof on the other side of the longitudinal centerline and aligned with said cord holes, the width and 25 depth of said notches being at least equal to the diameter of said lift cord, said notched edge of said slat being disposed at the bottom and overlapping the top edge of the slat below when the slats are tilted closed in one direction, said notch and said cord hole providing 30 a continuous open passageway for said lift cord when said slats are fully closed in said one direction, a pair of axially aligned pivoted members at the top and bottom of the blind adjacent said ladder tape, and a pair of parallel rods connected at their ends to said members on opposite 35 sides of and equidistantly from the pivot axis thereof and extending vertically along opposite sides of said slats, said members being rotatable so as to bring said rods in toward said slats to engage the same from opposite sides, thereby pressing said slats tightly together 40 in a vertical plane taken through the pivot axes of said pivoted members.
